UNITED STATES PATENT OFFICE

SAMUEL H. SHELLER, OF MARION, PENNSYLVANIA

FRUIT BASKET TOP APPLYING TOOL

Application filed September 16, 1929. Serial No. 392,885.

This invention relates to an improved tool for fastening fruit basket covers or tops to fruit baskets.

The common practice followed in applying the cover or top to a basket filled with fruit, is to bend the wire handles or loops carried by the basket, over the projecting ends of the slat on the cover or top. As baskets of fruit are usually packed slightly beyond their tops, to provide good packing and possible shrinkage or settling, considerable effort is required to bend the wire loops over the ends of the slat.

The object of the present invention is to provide an improved tool or "lidder" by which the foregoing operation can be quickly effected, in a more or less semi-automatic manner, with the expenditure of little manual effort on the part of the operator, beside insuring a tight fastening of the cover or lid.

When using my improved lidder or tool, one projecting end of the slat on the basket top or cover is inserted in one of the wire loops on the basket, after the loop has been suitably bent, and then the tool is engaged with the remaining projecting end of the slat while the lever or handle of the tool fulcrums on the side of the basket. The operation of the lever forces the remaining wire loop over the end of the tool and bends it so that it straddles the projecting end of the slat, at the same time closing the cover or lid and quickly effecting a secure fastening of the lid to the basket.

The present tool or lidder is adapted for use in fastening the lid or cover to a fruit basket which has been packed in the usual manner, that is, where packing starts on a facing former which is removed after the packed basket has been inverted to bring it to right side up position, or, for fastening the lid or cover to the basket when the method of packing contemplates the use of the basket cover itself as a facing former, and where no other facing former is employed, as set forth in an

application, Serial No. 392,884, for an improved method which I have executed of even date herewith, in which method the basket is wired or fastened to the cover when the basket is in inverted position.

Therefore, I have shown and described the tool when used in connection with the ordinary method of packing and also when used in connection with my improved method of packing.

While I have found in practice that the tool or lidder hereinafter described and which is shown in the accompanying drawings is well adapted to serve its purpose, nevertheless I do not limit the invention to the details thereof except where specifically recited in the claims.

In the accompanying drawings:

Figure 1, is a side elevation of a basket and its lid or cover in inverted position, illustrating how the tool is used in connection with a method of packing such as set forth in my aforesaid application, the parts being in the position where the closing action is starting;

Fig. 2, is a similar view illustrating the position of the parts when the closing action has been completed;

Fig. 3, is a side elevation illustrating the beginning of the closing action when the tool is used in connection with a fruit basket which has been packed by the use of a facing former which is afterward removed and the basket placed in upright position before the lid or cover is applied; and

Figs. 4 and 5, are detail views of opposite sides of the tool when in collapsed condition.

In Figs. 1 and 2, the present improved tool is shown in connection with a fruit basket 1, liner 2, top or lid 3, and cap 4 arranged and adapted for carrying out the final step involved in the new method of packing fruit set forth in my aforesaid application.

In Fig. 3, the tool is illustrated in connection with a fruit basket and lid or cover

wherein the lid is applied and fastened when the basket is in upright position.

Referring to Figs. 1 and 2, the basket 1 has the usual bendable wire loops or handles 5 which are intended to receive the ends 6 of the slat 7 of the lid whose ends project beyond the lid.

In using the tool, the basket having been inverted and telescoped over the liner 2 according to the method of my aforesaid application, one of the loops 5 is bent to receive one of the ends 6, it being understood that the fruit will cause the basket to be disposed substantially as shown, requiring considerable pressure to engage the remaining (right hand) loop or handle with the right hand end 6.

The tool is now brought into use to draw the basket and lid together and bend the right hand loop and slip it over the right hand end 6.

The improved tool mainly comprises three parts, namely, the hook 8, bender 9, and lever or handle 10. The hook 8 is hinged to the fulcrum end 11 of the lever 10, which is intended to bear on the side of the basket 1, by a bolt 12. The bender 9 is hinged to lever 10 by a bolt 13 intermediate the ends of said lever.

The bender 9 has connected thereto, as by rivets 14, for instance, the bending head 15 whose lugs 16 are connected by a cross-pin 17. The hook slides between the lugs 16 and under the cross-pin 17. Ears 18 on the head 15 serve as an abutment or stop to prevent the wire loops or handles 5 from slipping up over the tool during the bending and fastening operation.

When using the tool, as shown in Figs. 1 and 2, the hook 8 is slipped through the wire loop 5, when the tool is vertically arranged, and the end 19 of the hook engaged with the end 6 of the slat 7. With the fulcrum end 11 bearing on the side of the basket, as in Fig. 1, the operator presses the outer end of the lever 10 downwardly as shown in Fig. 2. This action forces the head 15 downwardly and draws the hook 8 upwardly, bending the wire loop or handle 5 inwardly and forcing it over the end 6 of slat 7 as the basket and lid are drawn together, as shown in Fig. 2. This action clears the loop 5 from the hooked end 19 by slipping it past the said end 19; consequently, the tool is freed of the loop 5 when the operation is complete.

In Fig. 3, when the basket is upright, the action of the tool is the same as previously described but, in this instance, the handle or lever 10 is pulled upwardly, instead of downwardly, as the tool is then arranged reversely to its position in Figs. 1 and 2.

What I claim is:

1. A tool for applying the cover to a fruit basket having wire loops or handles on the basket and projections on the cover, comprising a member adapted to exert a closing action on the cover, a second member cooperating therewith adapted to force the wire loops over a projection on the cover, said members being relatively movable and means for relatively shifting said members.

2. A tool for applying the cover to a fruit basket having wire loops or handles on the basket and projections on the cover, comprising a member adapted to exert a closing action on the cover, a second member cooperating therewith adapted to force the wire loops over a projection on the cover, said members being relatively movable, and means for relatively shifting said members.

3. A tool for applying the cover to a fruit basket having wire loops or handles on the basket and projections on the cover, comprising a hooked member whose hook is adapted to engage a projection on the cover, a second member cooperating therewith having a bender adapted to force the wire loop over and past the hooked end and over the projection on the cover, said members being relatively movable, and means for relatively shifting said members.

4. A tool for applying the cover to a fruit basket having wire loops or handles on the basket and projections on the cover, comprising a hooked member whose hook is adapted to engage a projection on the cover, a second member cooperating therewith having a bender adapted to force the wire loop over and past the hooked end and over the projection on the cover, said members being relatively movable, and means for relatively shifting said members.

5. A tool for applying the cover to a fruit basket having wire loops or handles on the basket and projections on the cover, comprising a hooked member whose hook is adapted to engage a projection on the cover, a second member having a bender adapted to force the wire loop over and past the hooked end and over the projection on the cover, said hooked member and a second member being slidable alongside each other, and said second member having means for guiding the hooked member and preventing the latter from separating from the second member during such sliding movements, and means for operating said members.

6. A tool for applying the cover to a fruit basket having wire loops or handles on the basket and projections on the cover, comprising a hooked member whose hook is adapted to engage a projection on the cover, a second member having a bender adapted to force the wire loop over and past the hooked end and over the projection on the cover, said hooked member and a second member being slidable alongside each other, and said

second member having means for guiding the hooked member and preventing the latter from separating from the second member during such sliding movements, and a lever 5 to which the hooked member and the second member are hinged and whereby they may be simultaneously shifted with a relative sliding and substantially parallel movement in opposite directions to effect the foregoing 10 operations.

In testimony whereof I affix my signature.
SAMUEL H. SHELLER.
